UNITED STATES PATENT OFFICE

99,635

DESIGN FOR AN AX HEAD

Howard A. Vaughan, Glencoe, Ill.

Application March 2, 1934, Serial No. 50,923

Term of patent 7 years

To all whom it may concern:

Be it known that I, Howard A. Vaughan, a citizen of the United States, residing at Glencoe, in the county of Cook and State of Illinois, have invented a new, original, and ornamental Design for Ax Heads, of which the following is a specification, reference being had to the accompanying drawing forming a part thereof, wherein—

Figure 1 is a perspective of an ax head embodying the new design;

Figure 2 is a front view; and

Figure 3 is a plan view.

The present design comprises as the principal and dominating features thereof an ax head comprising a blade portion and a head portion; said head portion having a rectangular surface positioned opposite said blade portion, on one end

of which surface is mounted a cylindrical hammer portion having a diameter greater than the width of the rectangular surface and extending above the rectangular surface a distance less than its diameter, said hammer portion being positioned with its cylindrical surface substantially tangential with one end of the rectangular surface and projecting beyond the sides of the head portion and merging into the sides thereof by means of facets.

I claim:

The ornamental design for an ax head, substantially as shown and described.

Signed at Chicago, Illinois, this 26 day of February, 1934.

HOWARD A. VAUGHAN.
